To all whom it may concern:

Be it known that I, Richard C. Marholz, a citizen of the United States, residing at Chicago, Illinois, post office address 1257 Fullerton Avenue, Chicago, Illinois, have invented a new, original, and ornamental Design for an Escutcheon Plate for a Radio Receiver, of which the following is a specification, reference being had to the accompanying drawing, forming part thereof, in which:

Fig. 1 is a front elevation of my new design for an escutcheon plate for a radio receiver.

Fig. 2 is a top plan view of the escutcheon plate.

Fig. 3 is an end elevation of the structure of Fig. 2.

I claim:

The ornamental design for an escutcheon plate for a radio receiver as shown.

RICHARD C. MARHOLZ.
